DRAW TABLE

Bror J. Swanson, Rockford, Ill., assignor, by mesne assignments, to Landstrom Furniture Corporation, Rockford, Ill., a corporation of Illinois

Application July 2, 1930, Serial No. 465,319

14 Claims. (Cl. 311—55)

This invention relates to tables of the type sometimes known as refectory tables but more properly termed draw tables.

Draw tables as heretofore constructed have been subject to certain objections, among which may be mentioned that the draw leaf could not be pulled out and returned as easily as desired, especially in the type of table where the top is arranged to drop down to the level of the draw leaves and must be raised to clear the leaves when they are to be returned. In that type of table, there was also the objection that the finish on the draw leaves was bound to be damaged by the abrasion with the under side of the top in the pulling out and returning of the leaves. Another objection has been that the draw leaves were apt not to lie flush with the ends of the top owing either to slight inaccuracy in construction to begin with or due to a certain amount of warpage after the table left the factory. Still other objections have been that the draw leaves were not very well supported in extended position and the hardware required in connection with the supporting of the leaves made for noisy operation.

The principal object of my invention is to provide a draw table which avoids the objections noted, the draw leaves being arranged to be pulled out and returned with ease and facility, being arranged for adjustment in their supports to make the same absolutely flush with the table top, and being, furthermore, operable quietly and supported in extended position as rigidly as the wooden construction of a table permits.

The invention is illustrated in the accompanying drawings, in which—

Figure 1 is a plan view of one end of a draw table embodying my invention;

Fig. 2 is a longitudinal, vertical section on an enlarged scale taken on the broken line 2—2 of Fig. 1;

Figs. 3 and 4 are similar sections but showing the draw leaf in Fig. 3 extended preparatory either to returning the same or to placing the same in operative position, and showing the same in Fig. 4 as returned to the out-of-the-way position;

Fig. 5 is an enlarged vertical, sectional detail taken on the line 5—5 of Fig. 2 looking in the direction indicated by the arrows; and

Fig. 6 is a vertical, sectional detail on the line 6—6 of Fig. 2 looking in the opposite direction.

The same reference numerals are applied to corresponding parts throughout the views.

The table illustrated has the top 10 rigidly supported on cross-members 11 on the frame composed of the usual side rails 12 and end rails 13. It will soon appear, however, that the improvements hereinafter described are applicable to a draw table of the type in which the top is arranged to be raised and lowered in the returning

and pulling out of the draw leaves. One of the two draw leaves provided in connection with the top at opposite ends of the table is shown at 14 and has a pair of laterally spaced parallel slides 15 fastened to the under side thereof and arranged to support the same in extended position. The construction employed at opposite ends of the table is the same so that the description can be confined to the one draw leaf shown and the parts cooperating therewith. The slides 15 are 10 slidably received in notches 16 provided in the end rail 13, the said notches being just deep enough so that the draw leaf clears the top of the end rail in sliding under the top. The cross-member 11 is so positioned that the draw leaf 15 comes into abutment therewith when the outer end lies flush with the end of the table top, as shown in Fig. 4. The inner ends of the slides 15 are each guided between blocks 17 and 18 fastened to the under side of the cross-member 11 and pins 20 19 are provided on the blocks 18 for reception in grooves 20 cut in the inner sides of the slides. The grooves extend lengthwise of the slides at the proper elevation to support the slides with the draw leaf disposed parallel with the table top 25 when the draw leaf is in the position shown in Fig. 4 or pulled out part way, but the inner ends of the grooves are curved downwardly, as shown in Figs. 2 and 3, so as to allow the draw leaf to come parallel with the table top when it is raised 30 to the operative extended position shown in Fig. 2. The tops of the slides are cut away, as indicated at 21, to clear the cross-member 11 in the movement of the draw leaf in either direction, the inner ends of the slides having the tops there- 35 of further cut down, as at 22, to clear the cross-member in the fully extended position of the slides. The construction thus far described is more or less common in draw tables and no invention is, therefore, claimed in these details excepting only in so far as they form a part of the novel combinations and arrangements herein- 40 after described.

Pins 23 are provided on the outer sides of the slides 15 for cooperation with brackets 24 mounted on the end rail 13 to support the slides holding the draw leaf 14 in extended operative position, as shown in Fig. 2. I am aware that sheet metal brackets have been provided in the past on the end rail to receive pins projecting from 50 the slides but they have not been satisfactory. For one thing, they were formed with hook-shaped projections into which the pins were arranged to be entered from in front of the brackets and that necessitated location of the seats 55 for the pins so far out with relation to the screws that served to fasten the brackets to the end rail that the strain imposed on the screws eventually caused them to loosen, and that naturally 60 threw the draw leaf out of proper relation to the

end of the table top. Furthermore, in pulling the draw leaf out, the pins would strike the fronts of the bracket and produce a disagreeable metallic sound, not appropriate for an article of furniture. Then, too, that form of bracket was not as strong as desired, the projecting portion having support from only one side of the slot into which the pin was arranged to enter, and consequently the brackets were apt to bend out of shape. These objections are avoided with the present invention in which each of the brackets 24 has the body portion 25 fastened by means of screws 26 to the end rail 13 and has a flange 27 extending at right angles thereto the full height thereof, the flange having a bayonet slot 28 cut therein from the back of the body 25 for reception of the pin 23. The end rail is cut away alongside the notch 16, as at 29, from a point well below the bracket to a point at the level of the upper end of the bayonet slot 28 so as to permit the pin 23 to be brought behind the bracket for entry into the slot therein. It will be observed in Figs. 2-4 that the open end of the slot is widened so as to facilitate entry of the pin therein and that the body portion 25 of the bracket is cut away, as at 30, to provide clearance for the end of the pin as it enters and leaves the slot. The seat for the pin formed by the closed end of the slot, by virtue of the arrangement just described, can be located very close to the plane of the body portion, as shown, and there is, therefore, little likelihood of the screws 26 being loosened. Furthermore, as the draw leaf is pulled out, the pins 23 do not strike anything metallic at the limit of the movement of the slides but come into abutment with the end rail in the cut out portions 29 thereof and the operation is, therefore, very quiet. Another objection to the other type of brackets, above mentioned, was that they could not be adjusted to bring the draw leaf flush with the end of the table top in case there happened to be some slight discrepancy in the construction of the table to begin with or in case the parts warped a trifle after the table left the factory. The brackets made in accordance with my invention may be adjusted to raise or lower either or both slides so as to bring the draw leaf exactly flush with the end of the table top. Referring to Fig. 50 it will be observed that each of the brackets 24 has elongated slots 31 in the body portion 25 thereof through which the screws 26 for fastening the bracket are entered. Thus, if the screws 26 are loosened the bracket may be adjusted bodily upwardly or downwardly to the exact position desired and can be held in that position by retightening the screws. The means for adjusting the bracket and holding the same in adjusted position comprises a jack screw 32 threaded in a hole 33 provided in a flange 34 projecting from the lower end of the body portion 25. The screw 32 has an elongated head 35 in which an annular groove 36 is provided for rotatably mounting the screw in a slot 37 provided in a flange 38 on a bracket 39 fastened, as by means of screws 40, to the end rail 13. It is believed to be obvious that in making an adjustment it is only necessary to loosen the screws 26 whereupon the screws 32 can be turned to raise or lower the bracket 24 the desired amount after which the bracket can be fastened in its adjusted position by retightening the screws 26. The adjustment is so simple that a mechanically unskilled person should have no difficulty in making the same. This adjustment is naturally of great ad-

vantage not only at the factory, to bring the draw leaf into alignment with the table top, but also in the sales-room or in the home, to true up the table in case the draw leaf gets out of alignment due to warpage.

It is believed the foregoing description conveys a clear understanding of all of the objects and advantages of my invention. The appended claims have been drawn with a view to covering all legitimate modifications and adaptations.

I claim:

1. In a draw table comprising a frame, a table top supported thereon, slides reciprocable on the frame and a draw leaf carried on the slides, the combination with said slides of means on the frame for making a quickly detachable connection therewith for supporting the same so that the draw leaf is disposed in coplanar relation with the top, said means comprising a bracket positioned alongside each of the slides and secured to the frame and having a slot provided therein opening from the back of the bracket, there being a pin projecting from the side of the slide arranged to be received in said slot, and the bracket being disposed so as to permit entry of the pin behind the bracket into the slot therein.

2. A draw table as set forth in claim 1 wherein each of the brackets is provided with vertically elongated slots through which screws for fastening the brackets to the frame are passed, thus permitting adjustment of the brackets for the purpose described.

3. A draw table as set forth in claim 1 wherein the brackets are vertically adjustable for the purpose described, the table including secondary brackets cooperating with the other brackets and secured in a predetermined fixed position on the frame, and screw means acting between the secondary brackets and the other brackets for adjusting the latter and holding the same in adjusted position.

4. A draw table as set forth in claim 1 wherein the brackets are provided with vertically elongated slots through which screws are entered for adjusting the brackets to the frame, the table including secondary brackets below the other brackets and secured to the frame in a predetermined fixed position, and screw means acting between the secondary brackets and the other brackets for adjusting the latter for the purpose described, the screws fastening the first mentioned brackets being arranged to be loosened prior to the adjustment and retightened after the adjustment.

5. In a draw table comprising a frame, a table top supported thereon and a draw leaf arranged to be placed in coplanar relation with the top, the combination with a cross-member of the frame and a slide attached to the draw leaf reciprocable in an opening provided in the cross-member, of a pin projecting laterally from the slide for supporting the same on the cross-member, and a bracket for cooperation with said pin comprising a body portion secured to the cross-member along side the opening for the slide and having a flange extending therefrom parallel with the slide, the flange having a blind slot provided therein opening from the back of the body portion, and the cross-member being cut away alongside the opening behind the body portion and to a point below the latter to permit passage of the pin behind the bracket and entry thereof into the slot.

6. A draw table as set forth in claim 5 wherein

the body portion of the bracket is provided with vertically elongated slots for the entry therethrough of screws or the like for fastening the bracket to the cross-member, whereby to permit adjustment of the bracket up or down for the purpose described.

7. A draw table as set forth in claim 5 wherein the bracket is vertically adjustable relative to the cross-member, the structure including a screw adjustment means fixed to the cross-member and cooperating with the bracket.

8. In a draw table comprising a frame, a table top supported thereon and a draw leaf arranged to be placed in coplanar relation with the top, the combination with a cross-member of the frame and a slide attached to the draw leaf reciprocable in an opening provided in the cross-member, of a pin projecting laterally from the slide for supporting the same on the cross-member, a bracket carried on the cross-member having a body portion and a flange projecting therefrom in a vertical plane parallel with the slide for reception of the pin thereon for support of the slide, said bracket having another flange projecting therefrom in a horizontal plane, a secondary bracket fixed to the cross-member below the first bracket having a horizontal flange projecting therefrom, and an adjusting screw rotatably mounted in one of the horizontal flanges and threadedly engaged in an opening provided in the other horizontal flange and arranged in the turning thereof to move the first bracket in one direction or the other with reference to the secondary bracket, there being vertically elongated slots provided in the body portion of the first bracket, and screws entered through said slots for fastening the same adjustably to the cross-member.

9. In an article of furniture, the combination with a frame member and another member arranged to be detachably secured thereto in a predetermined position transverse with respect thereto, the frame member having an opening therein for slidably receiving the other member, of a bracket comprising a body portion fixed to the frame member alongside the opening and having a flange projecting therefrom alongside of and parallel to the other member, there being a slot provided in said flange intermediate the ends thereof opening from the back of the body portion, and a pin projecting laterally from the other member and arranged to be entered in said slot for quickly removably supporting the member thereon.

55 10. In an article of furniture, the combination with a frame member and another member arranged to be detachably secured thereto in a predetermined position transverse with respect thereto, the frame member having an opening therein for slidably receiving the other member, of a bracket comprising a body portion fixed to the frame member alongside the opening and having a flange projecting therefrom alongside of and parallel to the other member, there being a slot provided in said flange intermediate the ends thereof opening from the back of the body portion, and a pin projecting laterally from the other member and arranged to be entered in said slot for quickly removably supporting the member thereon, the frame member having a portion thereof cut away alongside the opening from a point below the bracket behind the bracket up

to the level of the open end of the slot, whereby to permit approach of the pin toward the bracket from in front thereof and passage of the pin behind the bracket for entry in the slot.

11. In an article of furniture, the combination with a frame member and another member arranged to be detachably secured thereto in a predetermined position transverse with respect thereto, the frame member having an opening therein for slidably receiving the other member, of a bracket comprising a body portion fixed to the frame member alongside the opening and having a flange projecting therefrom alongside of and parallel to the other member, there being a slot provided in said flange intermediate the ends thereof opening from the back of the body portion, and a pin projecting laterally from the other member and arranged to be entered in said slot for quickly removably supporting the member thereon, the body portion of said bracket having vertically elongated slots provided therein, and screws or the equivalent passed through said slots for fastening the bracket to the frame member, the loosening of the screws permitting adjustment of the bracket up or down and the tightening of the screws serving to hold the bracket in adjusted position.

12. In an article of furniture, the combination with a frame member and another member arranged to be detachably secured thereto in a predetermined position transverse with respect thereto, the frame member having an opening therein for slidably receiving the other member, of a bracket comprising a body portion fixed to the frame member alongside the opening and having a flange projecting therefrom alongside of and parallel to the other member, there being a slot provided in said flange intermediate the ends thereof opening from the back of the body portion, and a pin projecting laterally from the other member and arranged to be entered in said slot for quickly removably supporting the member thereon, the body portion of said bracket having vertically elongated slots provided therein, and screws or the equivalent passed through said slots for fastening the bracket to the frame member, the loosening of the screws permitting adjustment of the bracket up or down and the tightening of the screws serving to hold the bracket in adjusted position, and means for adjusting said bracket comprising a secondary bracket fixed to the frame member below the first bracket, both of said brackets having horizontal flanges projecting therefrom, and screw means between said flanges arranged when turned in one direction to raise the first bracket relative to the second, and vice versa.

13. A metal fixture for extension tables comprising an attaching plate having a vertical flange projecting therefrom, the attaching plate having an opening provided therein forming the entrance to a slot provided in the flange extending forwardly from the attaching plate.

14. A metal fixture for extension tables comprising an attaching plate having a vertical flange projecting therefrom, the attaching plate having an opening provided therein forming the entrance to a slot provided in the flange extending forwardly from the attaching plate, the forward end of said slot extending downwardly to provide a depressed seat.

BROR J. SWANSON.
